UNITED STATES PATENT OFFICE.

CYRUS EVERE, OF BROOKLYN, NEW YORK, ASSIGNOR TO LIDGERWOOD MANUFACTURING COMPANY, OF NEW YORK, N. Y., A CORPORATION OF NEW YORK.

WINDING OR HOISTING ENGINE.

1,383,704.

Specification of Letters Patent. Patented July 5, 1921.

Application filed October 31, 1918. Serial No. 260,459.

To all whom it may concern:

Be it known that I, CYRUS EVERE, a citizen of the United States, residing at New York city, borough of Brooklyn, county of Kings, 5 and State of New York, have invented certain new and useful Improvements in Winding or Hoisting Engines, of which the following is a specification.

My invention relates to new and useful 10 improvements in winding or hoisting engines. Important objects of the invention are to provide a multi-drum hoisting or winding engine which will be particularly useful in connection with load hoisting and 15 transferring cableways, which will be light in construction, and therefore easily portable, which will be so constructed that it may be readily supported and operated on a vertical or otherwise arranged spar or post 20 constituting a support for one end of a cableway, which may be conveniently mounted in, and dismounted from its operative position on such spar or post, and in which improved means will be provided for connecting the 25 drums to, and disconnecting them from a source of power. Other objects of the invention will be apparent from the following description.

The invention consists in the new and useful 30 construction and combination of parts to be more fully described hereinafter, and the novelty of which will be particularly pointed out and distinctly claimed.

I have fully and clearly illustrated a preferred 35 embodiment of my invention in the accompanying drawings to be taken as a part of this specification, and wherein:

Figure 1 is a view in side elevation of one type of cableway in connection with which my improved hoisting and winding engine 40 is adapted to use, the latter being shown in side elevation.

Fig. 2 is a view in front elevation of my improved hoisting or winding engine.

Fig. 3 is a view in side elevation of the construction shown in Fig. 2.

Fig. 4 is a central longitudinal section through the drum shaft.

Referring to the drawings by characters 50 of reference, 1 designates a head spar or pole, and 2 designates a tail spar or pole for supporting the ends of a cableway, between which spar poles is suspended and

supported in any suitable manner the main 55 supporting cable or trackway 3 of the cableway. The poles 1 and 2 may be guyed by suitable guys shown at 4, 5, respectively. 6 designates the frame of a load carriage of any suitable construction, and having running wheels 7 traveling on the main 60 cable 3, and by which the carriage is supported on said main cable, said carriage also carrying a guide pulley or sheave 8 for a purpose to be presently described. On the head spar 1, is arranged a rotary guide 65 sheave 9, over which passes a traversing rope 10, the same extending parallel to the main cable and around a guide pulley or sheave 11 on the tail spar 2, from which point said rope 10 is doubled upon itself, as at 10', and 70 connected to the carriage 6 in any suitable manner as at 12. This rope 10 is operable, when a pull is exerted thereon, to traverse the carriage along the main cable or trackway 3 toward the tail spar or support 2. 75 13 designates a combined hoisting and traversing rope which is passed over a rotary sheave or pulley 14 on the head spar, and over the sheave or pulley 8 on the carriage, from which point said rope depends, as at 80 13', for connection by any suitable means to a load to be hoisted and transported. This rope 13 is operable to lift the load and to traverse the carriage toward the head spar. The above construction of cableway is illustrated and described merely by way of 85 exemplification, to show one type of cableway in connection with which my improved hoisting or winding engine is adapted to be used, and said cableway forms no part of my present invention, nor is said invention limited 90 in its scope to the use in connection with such a cableway.

I will now proceed to describe the improved winding or hoisting engine constituting my invention. 15 designates a supporting plate or bed adapted to be secured in vertical position to the head pole 1, said plate or bed being provided on its rear face with clamping members 16 adapted to engage the spar or pole 1, adjacent the bed plate, and with which clamping members coöperate clamping plates 17 arranged to engage the supporting pole 1 on the opposite side from said clamping members 16, 100 and be clamped in position by means of

headed bolts 18 passed through openings in the bed plate, and the clamping members 16 from the outer side of said bed plate, the bolts having threaded outer ends which pass 5 through openings in the said plates 17 and receive clamping nuts 19, by means of which the clamping members 16 and plates 17 may be made to firmly grip the pole 1 and hold the bed plate rigidly in position on the same. 10 On the bed plate is arranged and supported a rotary electric motor 21, the armature shaft 22 of which carries a pinion 23 which meshes with a gear 24 on a shaft 25, extending parallel to the armature shaft and 15 having its ends mounted in bearings 26 on outwardly or horizontally projecting brackets 27 on bed plate 15. 21^a designates a controller box for controlling the motor, said box being supported on a bracket member 20. Fixed to the shaft 25 is a driving pinion 28 arranged in mesh with a gear 29 mounted at approximately the longitudinal center of a horizontal shaft 30, mounted 20 to rock in bearings 31 on side brackets 32 projecting laterally from the bed plate 15. The gear 29 is mounted to turn loosely on the shaft 30, and is held against endwise movement thereon by split collars 32' arranged on opposite sides of the hub of said 25 gear, and seated in annular grooves 33 in said shaft, said split collars being immovable lengthwise of the shaft. The gear 29 is provided on its opposite faces with cone friction clutch elements 34, 35, respectively, held in position by bolts 36 let through the 30 web of the gear 29, as clearly shown in Fig. 4 of the drawings. On opposite sides of the gear 29 and mounted loosely on the shaft 30 to turn relative thereto, but capable of 35 movement longitudinally thereof toward and away from the gear, are drums 36, 37, one of which is adapted to have wound thereon the line 10, and the other to have wound thereon the line 13. The inner head 40 of each drum is provided with a lateral and outwardly projecting flange, shown respectively at 38, 38', and each flange having an internal cone clutch face, which faces serve 45 respectively, to engage with the elements 34 and 35 to connect the drums with the driving gear 29.

I will now describe improved means for causing movement of the drums lengthwise of the shaft 30, so as to connect either of 50 the same with the driving gear 29, so that one of said drums will be driven positively, and to separate or disconnect the other of the drums from the gear so that said other drum will not be driven, and may be held 55 against rotation. For this purpose the shaft 30 is provided at its opposite ends outside the said drums 36, 37 with thrust sleeves or collars 39, 40, threaded on the said shaft by means of an internal thread in each sleeve 60 or collar and an external thread 41 on the

shaft, the threads being arranged or directed in the same direction, as clearly shown in Fig. 4 of the drawings, for a purpose to be presently described. At one end, the shaft is provided with an extension 41^a, 70 to which is connected a hand lever 42 by means of which the shaft 30 may be rocked manually in either direction. When the shaft 30 is rocked in one direction, it will be operated to move the collar 39 lengthwise of the shaft toward the drum 36 to thrust the latter into frictional engagement with the gear 29, while the sleeve 40 will be moved simultaneously along the shaft in the same direction, but away from the drum 80 37 so as to relieve the frictional clutch engagement between the drum 37 and the gear 29, and permit the drum 37 to run free of said gear, this operation serving to clutch the drum 36 in driving engagement with the 85 gear, while the drum 37 is disconnected from the driving connection. If the shaft 41 is rocked in the opposite direction from that described, the collar 39 will be moved away from its drum 36 to permit the frictional 90 contact between said drum and the gear to be relieved, while the sleeve 40 will be moved in the same direction to thrust the drum 37 into frictional driving engagement with said gear. This arrangement is 95 such that when one drum is in frictional driving connection with the gear 29, the other drum will be disconnected therefrom, and may run free, or be held by a brake.

The outer face of each flange 38 on the 100 drums constitutes an annular brake surface with each of which cooperates a band brake shown at 42', 43, respectively, connected to the levers 44, 45, respectively, in a well known manner fixed to an operating shaft 105 46 operable by a hand lever 47. The levers 44, 45 are so located circumferentially and angularly of the shaft 46, for example, as shown in Fig. 3, that when the hand lever 47 is operated in one direction, the brake is 110 applied to one of the drums, and on the other hand, the brake is relieved from the other drum, while the reverse operation takes place when the lever 47 is moved in the reverse direction. By this arrangement either drum may be held under brake, and the other permitted to run unretarded, for example, when the outhaul line 10 is driven under power to outhaul the carriage, and its drum is connected to the driving gear, 115 the drum for the hoisting or outhaul line 13 will be disconnected from the driving gear 29, and may be held under brake, so as to prevent slack in the hoisting line, while the carriage is being outhauled. When the 120 carriage is outhauled to the desired position, the drum carrying the line 10 may be disconnected from the gear 29 and held by the brake, while the drum carrying the hoisting line 13 may be connected to the 125 130

gear and driven to take up the line to hoist the load, the brake not being applied to the inhaul drum.

- In order to hold the sleeve collars 39 and 5 40 against rotation, but permit their movement longitudinally of the shaft 41, I provide each sleeve collar with a flange 48 having a recess 49 adapted to be engaged by a bolt or pin 50 let through the side frame.
- 10 In order to provide for the adjustment of the collars lengthwise of the shaft to regulate the extent of movement thereof, and thereby insure proper movement of the drums relative to the gear 29, I may provide 15 each flange 48 with a plurality of the recesses 49, any one of which may, independently of the rotation of the shaft by rotation of the collar, be brought into position to be engaged by the pin 50 which is made re- 20 movable for the purpose stated.

What I claim and desire to secure by Letters Patent of the United States is:

1. In a winding engine, a shaft, a driving element loosely mounted on the shaft, a 25 drum loosely mounted on the shaft, friction clutch faces providing a driving connection between said drum and said driving element, means whereby rocking of the shaft in one direction connects said friction clutch faces, 30 and rocking in the opposite direction disconnects said friction clutch faces.
2. In a winding engine, a shaft, a driving element loosely mounted on the shaft, drums mounted loosely on the shaft on each side 35 of said element, friction clutch members for providing driving connection between each drum and said element, and means whereby rocking of said shaft connects one drum with the said element and disconnects the 40 other drum therefrom.
3. In a winding engine, a shaft, a driving element loosely mounted on the shaft, drums mounted loosely on the shaft on each side of said element, friction clutch surfaces be- 45 tween said drums and said element, thrust members, and means whereby rocking of the shaft operates said thrust members to place said drums in driving connection with the driving element.
- 50 4. In a winding engine, a shaft, a driving element loosely mounted on the shaft, drums mounted loosely on the shaft on each side of said element, friction clutch surfaces be- 55 tween said drums and said element, thrust members on the shaft, and means whereby rocking of the shaft operates said thrust members to place said drums in driving connection with the driving element.
5. In a winding engine, a shaft, a driv- 60 ing element loosely mounted on the shaft, drums mounted loosely on the shaft on each side of said driving element, friction clutch surfaces for providing a driving connection between each drum and said element, thrust 65 members threaded on the shaft, and means

whereby rocking of said shaft operates the thrust members to connect the drums with said driving element.

6. In a winding engine, a shaft, a driving element loosely mounted on the shaft, drums 70 mounted loosely on the shaft on each side of said driving element, friction clutch surfaces for providing a driving connection between each drum and said element, thrust sleeves threaded on the shaft, and means 75 whereby locking of said shaft operates the thrust sleeves to connect the drums with said driving element.

7. In a winding engine, a shaft, a driving element loosely mounted on the shaft, drums 80 mounted loosely on the shaft on each side respectively of said driving element, friction clutch faces for providing a driving connection between each drum and said element, means whereby rocking of said shaft connects one drum with the said element, and disconnects the other drum therefrom, brakes 85 operable on said drums, and operating means for the brakes whereby when one brake is applied the other is released. 90

8. In a winding engine, a shaft, a driving element loosely mounted on the shaft, drums mounted loosely on the shaft on each side of said driving element, friction clutch surfaces for providing a driving connection 95 between each drum and said element, thrust members threaded on the shaft, means to prevent rotation of said thrust members, and means whereby rocking of said shaft operates the thrust members to connect the 100 drums with said driving element.

9. In a winding engine, a shaft, a driving element loosely mounted on the shaft, drums loosely mounted on the shaft on each side respectively of said driving element, friction 105 clutch faces for providing a driving connection between each drum and said element, thrust sleeves threaded on the shaft and respectively engaging the opposite ends of said drums from the ends adjacent the driving 110 element, the threads between the sleeves and the drums being so directed to cause the thrust sleeves to move simultaneously in the same direction, and manual means for rocking said shaft, whereby the thrust sleeves are 115 moved to connect one drum to the driving element, and to relieve the connection between the other drum and the driving element.

10. In a winding engine, a vertically disposed bed plate having means securing the 120 same to a pole or spar, a motor on the bed plate, and having a horizontally disposed armature shaft, a driving shaft above the motor and geared to the armature shaft, a horizontal drum shaft, a gear mounted loosely on and rotatable relative to said shaft, drums mounted loosely on the shaft on opposite sides of said gear, friction clutch surfaces for providing a driving connection between said drums and said gear, thrust 125 130

members on the drum shaft and manually operative means for rocking the drum shaft, and connections between the thrust members and the drum shaft whereby rocking 5 of the latter operates the thrust members to connect one drum with the gear, and disconnect the other drum therefrom.

In testimony whereof I have hereunto signed my name in the presence of two subscribing witnesses.
